H. O. BAKER

LAMP AND LOUD SPEAKER

Filed April 16, 1927

INVENTOR.

Harold O. Baker,

BY
Geo. P. Kimmel.
ATTORNEY.

UNITED STATES PATENT OFFICE.

HAROLD O. BAKER, OF PONTIAC, MICHIGAN.

LAMP AND LOUD SPEAKER.

Application filed April 16, 1927. Serial No. 184,379.

This invention relates to a combined lamp and loud speaker, and the primary object thereof is to provide a new, artistic and novel article for the purpose had in view.

Further objects of the invention are to provide, in a manner as hereinafter set forth a combined lamp and loud speaker, which is simple in its construction and arrangement, strong, durable, compact, ornamental, attractive in appearance, thoroughly efficient in its use, and comparatively inexpensive to set up.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is an elevation of a combined lamp and loud speaker in accordance with this invention.

Figure 2 is a vertical sectional view thereof partly broken away.

Figure 3 is a fragmentary view in perspective of the horn.

Figure 4 is a top plan view of the base of the device.

A combined lamp and loud speaker, in accordance with this invention, comprises a base formed of an annulus 1 provided with a plurality of supporting legs 2. Formed integral with the inner face of the annulus 1, at a point below the top edge of the latter, is a support 3 provided with a centrally arranged opening 4 and an opening 5 adjacent the opening 4. That part of the annulus 1, which extends above the support 3, provides a vertically disposed annular flange 6. The annulus 1 and legs 2 in vertical section are of compound curvature and the legs 2 extend outwardly with respect to the annulus 1. Mounted upon the support 3 and confined by the flange 6 upon the base is a hollow pedestal 7, formed with a flat bottom 8 provided with a centrally disposed opening 9 and an opening 10 adjacent the opening 9. The opening 10 registers with the opening 5 when the pedestal 7 is mounted on the base. The opening 9 is of greater diameter than

the diameter of the opening 4. The openings 4 and 9 communicate with each other and the opening 9 is disposed concentrically with respect to the opening 4. The upper end of the pedestal is open as indicated at 11. As shown the pedestal 7 is set up as tapering in opposite directions or in other words inversely tapered and one of the tapered parts of the pedestal 10 is indicated at 12 and the other part is indicated at 13. The part 12 is of greater length than the part 13. The part 12 gradually increases in diameter from its lower end to its point of joinder with the part 13 and the latter decreases in diameter from its point of joinder with the part 12 to the upper end of the pedestal. The upper terminal portion of the part 13 is flared slightly.

The loud speaker unit is indicated at 14 and which is mounted on the upper face of the support 3 and extends down through the opening 4. That part of the unit 14 which is mounted upon the support 3 is surrounded by the wall of the opening 9 and is of the same height as the height of the wall of the opening 9. The leading-in wires to the unit 14 are indicated at 15 and extend from the base between a pair of legs 2.

Connected with and extending upwardly from the unit 14 is a cone-shape horn 16 which is of a length to project a substantial distance above the top of the pedestal 7. Arranged at the upper end of the horn 16 and maintained in spaced relation thereto are illuminating elements 17 in the form of electric lamps. The leading-in wires for each element 17, as indicated at 18 are secured to the periphery of the horn 16 and said wires extend down through the openings 10 and 5 and from the base 1 between a pair of legs 2. The leading-in wires 18 extend through bendable tubings 19 possessing the characteristic to maintain the elements 17 in a position shown in Figure 2, and also whereby the elements 17 can be adjusted to any desired angular position or other position with respect to the horn 16.

Connected to the periphery of the horn 16, at the upper end thereof, is a set of spaced outwardly inclined upstanding supporting arms 20 of appropriate height and which terminate in a band 21. The upper end of each of the arms 20 is angularly disposed as at 22 to provide a seat. Mounted on the seat 22 and surrounded by the band 21 is a head-piece 23 provided with an axially ar-

ranged protuberance 24 for extension through a supporting spider 25 which provides a suspension means for a frusto-conical shade 26.

5 The pedestal 7, as well as the shade 26 is ornamented as indicated at 27, 28 respectively. The horn 16 can be made of wood, fibre, metal or rubber if the same is preferred, and that the opening at the upper 10 end of the pedestal can be of any desired diameter.

The combined lamp and loud speaker, in accordance with this invention provides an article which when used will enhance the 15 appearance of a room, as the article is of the ornamented type and unusually pleasing to the eye, then at the same time it conceals the loud speaker element and provides in appearance a table or desk lamp without 20 one seeing the loud speaker, even though the latter be active and therefore it is thought the many advantages of a combined lamp and loud speaker, in accordance with this invention, can be readily understood, 25 and although the preferred embodiment of the invention is as illustrated and described, yet it is to be understood that changes in the details of construction can be had which will fall within the scope of the invention 30 as claimed.

What I claim is:

1. In an article for the purpose set forth, supporting means, a horn mounted therein and extending thereabove, a set of upstanding arms secured to and projecting above 35 the upper end of said horn, illuminable elements suspended adjacent the upper end of the horn, a band connected to said arms, and means mounted on the arms and surrounded

by the band for suspending a lamp shade. 40

2. In an article for the purpose set forth, supporting means, a horn mounted therein and extending thereabove, a set of upstanding arms secured to and projecting above 45 the upper end of said horn, illuminable elements suspended adjacent the upper end of the horn, a band connected to said arms, means mounted on the arms and surrounded by the band for suspending a lamp shade, 50 said means being removable.

3. In an article for the purpose set forth, supporting means, a horn mounted therein and extending thereabove, a set of upstanding arms secured to and projecting above 55 the upper end of said horn, illuminable elements suspended adjacent the upper end of the horn, a band connected to said arms, means mounted on the arms and surrounded by the band for suspending a lamp shade, 60 said horn being conoidal in contour throughout and said arms projecting outwardly at an inclination.

4. In an article for the purpose set forth, supporting means, a horn mounted therein and extending thereabove, a set of upstanding arms secured to and projecting above 65 the upper end of said horn, illuminable elements suspended adjacent the upper end of the horn; a band connected to said arms, means mounted on the arms and surrounded by 70 the band for suspending a lamp shade, and a loud speaker element mounted in the lower portion of said supporting means and connected to the horn.

In testimony whereof, I affix my signature 75 hereto.

HAROLD O. BAKER.
